BAG

Raymond Mills, Gloversville, N. Y., assignor to
 The Locktite Co., Inc., Gloversville, N. Y., a
 corporation of New York

Application October 3, 1934, Serial No. 746,715

3 Claims. (Cl. 150—33)

My invention relates to bags and particularly that type carried by women for holding small articles, commonly known as "costume" bags.

Bags of this type which are constructed without handles are usually carried in the hand or under the arm. When conditions arise necessitating the free use of both hands and arms it is necessary to lay the bag down with possible loss, due to forgetfulness or premeditated theft, particularly where such necessity arises in a public place. It is therefore the purpose of my present invention to provide a bag of this type having a ring handle element which can be concealed when it is desired to carry the bag in the hand or under the arm as a "tailored" bag and engaged over the wrist when it is desired to carry the bag as a "sports" bag or to secure free use of the hands and arms for a desired purpose without laying the bag down upon some supporting member such as a table.

In the drawing chosen to illustrate my invention, the scope whereof is set forth in the appended claims:

Figure 1 is a view in elevation of a bag constructed in accordance with my invention and showing the ring handle exposed and ready to be engaged over the wrist;

Figure 2, a section on the line 2—2 of Figure 1;

Figure 3, a side edge view with the ring handle concealed;

Figure 4, a top view showing the zipper closure of the bag, and

Figure 5, a fragmental perspective view showing the concealing pocket for the ring handle.

Referring to the drawing my improved bag is shown as comprising a flexible outer body portion 10 and an inner lining 11, said body portion may be fabric or leather or any other suitable desired flexible material. The open and closed status of the mouth of the bag is controlled by operating a "zipper" fastening structure 12. In the body portion 10 at one side edge of the bag I provide a slit 13 of desired length and along each edge of the slit a flap 14 is located. These flaps 14 are preferably of the same material as the body portion so as to modify the presence of the slit by screening the lining from observation through the slit and may be made integral with or attached to the body portion by stitching as desired. The flaps 14 are stitched together along their free edges to form a pocket structure lying between the body portion 10 and inner lining 11. The ring handle of the bag is indicated at 15 and is retained to the bag by a flexible strap 16 which passes through the ring 15 and bridges the mouth of the pocket formed by the flaps 14,

said strap being suitably secured at its ends to the body portion 10 on opposite sides of the slit respectively. It will be obvious that such construction provides for retaining the ring to the bag at all times and permits said ring to be moved to positions outside the bag and within the pocket. In addition to the utility of my invention previously referred to it may be noted that when the ring handle element is within the pocket it is protected against breakage and prevented from marring furniture in the event the bag is thrown carelessly upon a table or the like.

While I have shown the use of two flaps and the formation of a pocket by stitching the flaps together I desire to point out that such stitching could be omitted and the flaps left free. Furthermore, the slit in the body portion may be located at other points than the side edge with only one flap employed and directed across the slit so as to screen the lining of the bag from view through the slit.

I claim:

1. A bag comprising a flexible outer body portion, inner lining and means for opening and closing the mouth of the bag, said body portion having a slit therein, a flap along each edge of the slit extending inwardly between the body portion and lining and stitched together along their edges to provide a pocket, a ring, and flexible means retaining the ring to the bag and permitting movement of the ring to and from positions outside the bag and in said pocket.

2. A bag comprising a flexible body portion, inner lining and means for opening and closing the mouth of the bag, said body portion having a slit in one side edge, a flap along each edge of the slit extending inwardly between the body portion and lining and stitched together along their edges to provide a pocket, a ring, and flexible means retaining the ring to the bag and permitting movement of the ring to and from positions outside the bag and in said pocket.

3. A bag comprising a flexible body portion, inner lining and means for opening and closing the mouth of the bag, said body portion having a slit in one side edge, a flap along each edge of the slit extending inwardly between the body portion and lining and stitched together along their edges to provide a pocket, a ring, and means bridging the mouth of the pocket and extending through the ring to retain the latter to the bag and permitting movement of the ring to and from positions outside the bag and in said pocket.

RAYMOND MILLS.
